SIGHT FEED CONTROL DEVICE

Charles B. Ware, Feasterville, Pa.

Application October 7, 1932, Serial No. 636,762

2 Claims. (Cl. 218—38)

The principal object of this invention is to provide an improved device for feeding measured quantities of one liquid to another circulating in or flowing through a fluid system.

Another object of the invention is to provide a device of the stated character incorporating visual means for effecting the required feed adjustments.

In the attached drawings:

Figure 1 is a diagrammatic view illustrating a fluid system provided with a device made in accordance with my invention;

Fig. 2 is a plan view of the system shown in Fig. 1;

Fig. 3 is a side elevation of my device;

Fig. 4 is a section on the line 4—4, Fig. 3;

Fig. 5 is a section on the line 5—5, Fig. 3, and Fig. 6 is a section on the line 6—6, Fig. 5.

With reference to Figs. 1 and 2 of the drawings,

1 is a centrifugal pump the intake of which may be considered, for purposes of illustration, to be connected through a pipe 2 with a swimming pool. From the pump 1 water withdrawn from the swimming pool passes through a pipe 3 to a filter 4, and thence through a pipe 5 is returned to the swimming pool.

In the treatment of water in swimming pools, it is frequently desirable to introduce small quantities of alum, copper sulfate, chloride of lime or other chemical substance. The prior method of introducing these materials has proven extremely wasteful by reason of inability to accurately regulate the quantities introduced, and since for effectiveness a certain minimum amount is required, it is necessary, in order to insure effectiveness, to introduce larger quantities than are strictly necessary.

In accordance with my invention, I provide a tank 6 which is partially filled with alum as illustrated. From the tank 6 a pipe 7 extends to the pipe 3, which as previously described connects the pump 1 with the filter 4. As illustrated, the pipe 7 extends downwardly through the tank and through the mass of alum therein to a point adjacent the bottom, the lower end portion of the pipe preferably being perforated. A pipe 8 enters the top of the tank, this pipe entering the bottom of a casing 9, shown in Figs. 3 to 6 inclusive. As illustrated, the casing comprises a base member 11 having a port 12 extending therethrough from top to bottom. The lower end of this port 12 is threaded, as shown in Fig. 6, for reception of the pipe 8. Mounted on the base member 11 is a glass dome 13 in the form of an inverted cup, this member being held in place upon the base

11 by means of a yoke 14 made, for example, of flexible wire, the inturned extremities 15 of this yoke entering apertures in the peripheral surface of the base 11. At its upper end the yoke carries fixed thereto a stud 16 which projects downwardly and carries a nut 17. A block or disk 18 rests in a socket 19 in the top of the dome 13 and has in its upper end a recess for reception of the lower extremity of the stud 16. By turning the nut 17 down against the top of the block 18, pressure is exerted upon the top of the dome 13, forcing it downwardly upon the base 11, a gasket 21 being provided between the lower edge of the dome and the base 11 to insure a hermetically sealed joint. The dome 13 may be removed by backing off the nut 17 and flexing the ends of the yoke 14 outwardly to free the inturned extremities from the apertures which they normally occupy in the base 11.

As shown in Fig. 5, the base 11 has at one side a tapped recess 22 which communicates through a passage 23 with a second tapped recess 24. From the bottom of this latter recess a channel 25 (see Fig. 6) extends to the upper surface of the base 11 in the interior of the dome 13, and a tube 26 fitted into the upper end of the channel 25 extends upwardly in the interior of the dome with its upper end turned over and downwardly, as clearly illustrated. The recess 24 receives the body member 27 of a needle valve. The stem 28 of this valve, which is threaded into the body member 27, being adapted to cooperate with the terminal end of the passage 23 to restrict the latter as required. As shown in Fig. 5, this stem is adjustable through a knurled head 29. The recess 22 receives one end of a duct 31 which, as shown in Fig. 2, connects with a pipe 32, and this pipe is connected with a source of water pressure exceeding the pressure of the water in the pipe 3 produced by the pump 1.

Under the foregoing conditions, assuming a circulation of water through the system 1—2—3—4—5, and assuming further the imposition of water pressure upon the pipe 32 in excess of the pressure in the aforesaid system, water necessarily will be forced through the pipe 31, the passage 23, the channel 25, and tube 26 to the interior of the dome 13, flow of water into the dome from the tube 26 being visible through the transparent walls of the casing. This water passes through the port 12 and pipe 8 to the top of the container 6, and passes downwardly through the alum bed in the latter to the bottom, and thence through the pipe 7 to the pipe 3 of the circulating system. By adjustment of

the needle valve 28, the flow of water through the alum bed may be regulated, and the visibility of the flow through the transparent casing 13 makes possible entirely accurate feeding of the alum to the fluid system. It will be apparent that the air confined in the upper part of the container 6 and in the dome 13 prevents accumulations of water in the tank 6 from passing upwardly into the dome 13 and destroying the sight feed 10 from the tube 26. At the same time, by reason of the preponderance of pressure in the pipe 32 over the pressure in the pipe 3, the feeding of the alum water through the pipe 7 to the fluid system must necessarily be continuous.

15 The device while simple in form is extremely effective for the intended purpose permitting highly accurate regulation of the alum water passing into the fluid system. A practical advantage of the device is the material saving in 20 alum over a given period of time.

25 The system may be extended to the measured introduction of other chemicals, and in Figs. 1 and 2, I have illustrated an extension of the system for introduction, for example, of soda to the water circulating through the filter system. For this purpose, there is necessary a mere duplication of the container 6 of the sight feed device 9, as shown in broken lines. In this instance, the 30 pipe passing from the said bed to the filter system enters the pipe 5, since in this instance it is

neither necessary nor desirable that the material introduced pass through the filter 4.

I claim:

1. A device of the character set forth comprising a base, a transparent dome, means for detachably securing the dome on the base, said base having intake and discharge ports communicating with the interior of said dome, together with recesses communicating with each other and one of which is in continuous communication with the said intake port, a duct extending upwardly in the interior of said dome from the intake port, and an adjustable valve secured in the last-named of the said recesses and controlling the flow of fluid through said intake port. 10

2. In a fluid system, the combination with a duct, and pressure means for forcing fluid through said duct, of a container for a soluble chemical having an air space at the top thereof, a duct establishing communication between the first-named duct and the container at a point in the latter below said air space, a transparent casing constituting an air trap above the top of said container and in communication with said air space, and means including a drip device for introducing regulated quantities of a liquid solvent for said chemical into the transparent casing under a pressure in excess of the pressure in the said first-named duct. 20
